UNITED STATES PATENT OFFICE.

JOHN F. MONAHAN, OF PEORIA, ILLINOIS.

GRAIN-DRIER.

1,285,779.

Specification of Letters Patent. Patented Nov. 26, 1918.

Application filed May 8, 1918. Serial No. 233,289.

To all whom it may concern:

Be it known that I, JOHN F. MONAHAN, a citizen of the United States, residing at Peoria, in the county of Peoria and State of Illinois, have invented certain new and useful Improvements in Grain-Driers, of which the following is a specification, reference being had to the accompanying drawings.

This invention relates to driers, and particularly to mechanism for drying grain or like material.

The general object of the invention is to provide a mechanism of this character comprising a plurality of drier sections, which may be assembled in any desired number, the drier sections being arranged in a compact series, and means being provided whereby the grain or like material may be carried through the drier sections successively.

A further object is to provide a construction of this character in which the grain is carried through a series of drying sections, each section being surrounded by a steam jacket, the steam jacket in turn being surrounded by a hot air jacket, and means being provided for removing moist air from the grain as it passes along said drier section.

A further object of the invention is to provide a construction of this character wherein the grain is caused to travel along each drier section by means of a longitudinally extending screw conveyer, the screw conveyer having a hollow shaft which is heated by steam.

A further object is to provide improved means whereby live steam or exhaust steam may be used for heating the drier sections, and whereby the steam after it has done its work may be withdrawn.

Another object is to provide a drier comprising a plurality of longitudinally extending drier sections arranged in vertical series, through which the grain is carried successively, the arrangement being such that while the grain will travel over a relatively long path, the drier sections will take up relatively little room.

Other objects will appear in the course of the following description.

My invention is illustrated in the accompanying drawings, wherein:—

Figure 1 is a side elevation of a grain drier constructed in accordance with my in-

vention, the drying sections being partly broken away and partly in section; 55

Fig. 2 is a section on the line 2—2 of Fig. 1;

Fig. 3 is a section on the line 3—3 of Fig. 1; and

Fig. 4 is an enlarged fragmentary section 60 of one end of the drier sections.

Referring to these drawings, it will be seen that the drier as illustrated is shown as formed of three drier sections, designated A, B and C respectively. These drier sections are all alike and, therefore, the description of one drier section, as for instance the drier section A will apply to all the other drier sections. While I have illustrated three of these sections, it will be understood 70 that more or less of the sections may be used, if desired. Each section comprises a centrally disposed longitudinally extending pipe 10 terminating at one end in a receiving chamber 11 and at its opposite end in a 75 discharge chamber 12. The receiving chamber has a grain inlet branch 13, while the discharge chamber 12 is connected to the grain inlet branch 13 of the next adjacent drying section. 80

Surrounding the pipe 10 and spaced therefrom is a pipe 14 and surrounding the pipe 14 and spaced therefrom is an outer pipe 15. Between the pipe 10 and the pipe 14, a steam space *a* is provided in which live or 85 exhaust steam may circulate and between the pipe 14 and the pipe 15 is a space *b* within which air may circulate, this air being heated by contact with the steam pipe 14. These pipes 10, 14 and 15 may be connected to the chambers 11 and 12 in any suitable manner so as to hold them in spaced relation, and the opposite ends of the sections may be supported in any desired manner, though I have illustrated for this purpose 90 a rack 16, which rack is formed of a single piece of metal bent to form a plurality of section embracing portions 17 and formed at its lower end with the feet 18, whereby it may be attached to the floor. Two of these 100 racks are shown though more of these racks may be used. Of course these racks have the same number of embracing portions 17 as there are heating or drying sections.

Passing longitudinally through the pipe 105 10 of each section and through the cham-

bers 11 and 12 is a hollow shaft 19 which carries upon it the screw conveyer 20 of any suitable character. At one end this hollow shaft is supported in a bearing 21 and has attached thereto the gear wheel 22. These gear wheels mesh with each other, as illustrated in Fig. 1, and any suitable means may be used for driving this train of gear wheels. As before stated, the shaft 19 is hollow and this shaft is connected with a source of live or exhaust steam in a manner which will be later stated.

For the purpose of carrying live or exhaust steam to the space *a* between the pipes 15 10 and 14, I provide a pipe line 23, which is connected by a pipe 24 to a source of live steam and by a pipe 25 to a source of exhaust steam. Under ordinary circumstances, the pipe 23 will be a 3" steam pipe, 20 the pipe 24 will be a 2" steam pipe and the pipe 25 carrying the exhaust steam will be a 4" pipe. A pressure regulating valve 26 may be disposed in the supply pipe 24 and, of course, this pipe is to be provided with 25 the usual controlling valve 27. The exhaust steam supply pipe is also provided with the controlling valve 28. Leading from the pipe line 23 are a plurality of branch pipes 29, one for each of the sections, passage through which is controlled 30 by a valve 30. These branch pipes lead through the space *b* and into the space *a*. Extending from the space *a* of each of the drying sections is an exhaust pipe 31, this 35 pipe communicating with the bottom portion of each space *a* by means of branches 32 and extending to a steam trap 33 of any suitable character, there being a valve 34 in this exhaust pipe line whereby passage 40 through the pipe 31 to the steam trap may be controlled.

For the purpose of feeding steam to the hollow shaft 19 of the steam conveyer, I provide a branch pipe 35 leading from the 45 pipe line 3 and communicating with one end of each tubular shaft 19. A swiveled or rotative joint 36 is provided at these points so that the shaft 19 may rotate without breaking its connection with the pipe 35. At the 50 opposite end of each shaft 19 there is provided an exhaust pipe 37 also having a swiveled connection with the several tubular shafts 19, this exhaust pipe 37 communicating with the branch 38 leading into the pipe 55 31, the adjacent portions of the hollow shafts being supported in bearings 21^a.

For the purpose of forcing warm dry air into the several drying sections and withdrawing the moist air from the grain as it 60 passes along the several drying sections, I provide the fans 39 and 40. The fan 39 is a suction fan and is connected by the suction pipe 41 to the several chambers 11. The fan 40 is connected by a suction pipe 43 to 65 the space *b* of each drier section and draws

warm dry air from the space *b* and forces it by pipe 42 into the several chambers 12 and thus through the several drying sections. Thus it will be obvious that moisture will be withdrawn from the grain as it is 70 dried and a constant circulation of warm, dry air will be secured.

The operation of this mechanism will be understood from the drawing. The grain from any suitable source is discharged into 75 the inlet pipe 13 of the first section of the series, and then is carried along within the pipe 10 by the screw conveyer. While being carried along this pipe, it is heated by the steam surrounding the pipe 10 and also 80 by the steam within the hollow shaft 19 of the screw conveyer. When the grain reaches the end of the first section, it is discharged into the inlet 13 of the next section and is then carried back in a direction 85 reverse to that in which it was first moved until it reaches the end of the second section and is then discharged into this second section and carried again in a reverse direction until it is discharged from the third 90 section. Of course it will be obvious that more sections may be used than three. While the grain is passing through the several drying sections, it is not only submitted to the heat of the steam, but the vapors given 95 off by the grain are being constantly removed by the suction fans 39 and 40 so that by the time the grain has passed through the last section it is fully dried.

It will be noted that this grain drier has 100 a forced feed and that the grain has to travel a distance of approximately six feet through a hot steam heated pipe through which hot air is being drawn, the grain traveling around a hot steam pipe 19. The conveyer 105 carries the grain along over the hot shaft while at the same time hot air is blown through the grain and the hot moisture laden air is drawn off. No heat is wasted in this grain drier and fuel is accordingly 110 saved. If an exhaust steam is used as a heating medium, this steam is exhausted into the open air where it is used but if live steam is used, the steam is condensed and the water is returned to the boiler. The construction is easy to erect and being made in 115 units may be of any desired size. It requires only one attendant to operate this drying plant.

It will be seen that the apparatus is 120 formed with a plurality of units, each having the same character, these units being such that they may be readily assembled to form a complete machine having any number of units.

While I have illustrated the particular arrangement for steam pipes and air exhaust pipes, I do not wish to be limited to this exact arrangement, as it is obvious that the particular arrangement of pipes will de- 125 130

pend somewhat upon the plant in which the apparatus is installed and that, therefore, my drawing with regard to the arrangement of the steam pipes and air withdrawing pipes is very largely merely illustrative.

Having described my invention, what I claim is:

1. A grain drier comprising a grain pipe section having closed chambers at its ends, one of the chambers being provided with a grain inlet opening and the other with a grain outlet opening, a steam pipe surrounding the grain pipe, means for circulating steam in the space between the grain pipe and the steam pipe, a tubular shaft passing longitudinally therethrough and having thereon a screw conveyer, means for causing the circulation of steam through the hollow shaft, and a hot air pipe surrounding the steam pipe.

2. A grain drier comprising a grain pipe section having closed chambers at its ends, one of the chambers being provided with a grain inlet opening and the other with a grain outlet opening, a steam pipe surrounding the grain pipe, means for circulating steam in the space between the grain pipe and the steam pipe, a tubular shaft passing longitudinally therethrough and having thereon a screw conveyer, means for causing the circulation of heating fluid through the hollow shaft, a hot air pipe surrounding the steam pipe, and means for causing a circulation of hot air in the space between between the hot air pipe and the steam pipe.

3. A drying apparatus including a grain drying pipe having an inlet at one end and an outlet at the other, a heating pipe surrounding the grain drying pipe, a tubular shaft extending through the grain drying pipe and carrying the screw conveyer, means for rotating the tubular shaft, means for supplying heating fluid to the heating pipe and to the tubular shaft, and means for

withdrawing heated vapor from opposite ends of the grain drying pipe.

4. A drying apparatus including a grain drying pipe, a surrounding steam pipe, and a surrounding hot air pipe, said grain drying pipe having a grain inlet at one end and an outlet at its opposite end, means for delivering steam to the steam pipe, means for positively withdrawing hot air and vapors from the interior of the grain pipe and means for withdrawing air from the hot air pipe and forcing the air so withdrawn into the grain pipe.

5. A drier of the character described comprising a plurality of parallel horizontal sections, each section comprising a grain drying pipe, an exterior steam pipe, and an exterior hot air pipe, grain boxes into which the ends of the grain pipes open, one of said boxes having a grain inlet and the other having a grain outlet, the outlet of one box communicating with the inlet of the box just below, racks operatively engaging the several sections and holding them in parallel spaced relation to each other, shafts passing through the several grain pipes, the shafts being hollow and carrying intermeshing gears, screw conveyers mounted on the several shafts, means for supplying steam to the steam pipes of the several sections and to the several shafts, means for carrying off steam from the steam pipes and the several shafts, a suction fan communicating with the several grain boxes at one end of the drier, and a suction fan communicating with the several boxes at the opposite end of the drier and with the several hot air pipes.

In testimony whereof I hereunto affix my signature in the presence of two witnesses.

JOHN F. MONAHAN.
